UNITED STATES PATENT OFFICE.

CURT R. BURKHARDT, OF TEANECK, NEW JERSEY, ASSIGNOR OF ONE-HALF TO JOHN A. SCHARWATH, OF ELIZABETH, NEW JERSEY.

PRESS-MOLD.

1,291,395.

Specification of Letters Patent. Patented Jan. 14, 1919.

Application filed September 1, 1917. Serial No. 189,405.

To all whom it may concern:

Be it known that I, CURT R. BURKHARDT, a citizen of the United States of America, and a resident of Teaneck, Bergen county, 5 and State of New Jersey, have invented certain new and useful Improvements in Press-Molds, of which the following is a specification, reference being had to the accompanying drawings, forming a part thereof.

10 My invention relates to molds suitable for use in the manufacture of asbestos cement shingles, and like articles; and has special reference to such as are intended for use in a press.

15 In my copending application Serial No. 101,461 filed June 2, 1916, I have shown and described a hydraulic press particularly adapted for use in the manufacture of asbestos cement shingles.

20 One object of my invention is to provide a simple and improved mold suitable for use in a press of this character.

Another object is to provide a mold of the 25 character above indicated, that shall be adapted to produce tapered shingles of uniform density without subjecting the press to improper strains.

Another object is to provide an asbestos cement shingle having a tapered formation 30 but at the same time having a substantially uniform distribution of weight throughout its length.

In order that my invention may be thoroughly understood, I will now proceed to 35 describe the same in the following specification, and then point out the novel features thereof in appended claims.

Referring to the drawings:

40 Figures 1 and 2 are sectional elevations at right angles to each other, of a press equipped with a mold which constitutes an embodiment of my invention.

Figs. 3 and 4 are transverse sectional views at right angles to each other showing 45 the mold and the press members drawn to a larger scale, Fig. 3 being taken on the line 3—3 of Fig. 5.

Fig. 5 is a partial plan view of the mold shown in Figs. 3 and 4, and

50 Figs. 6 and 7 are perspective views of a shingle which is produced by the mold illustrated in the previous figures and constitutes an embodiment of my invention.

Referring to Figs. 1 and 2, 10 designates 55 the base of the press having a bottom flange

11 by which it is bolted or otherwise secured to the floor or foundation. 12 designates a plunger, 13 a stationary press head at the top, 14 and 15 removable molds and 16 and 17 side frames or racks in which the molds 60 are supported when not in the press.

The base has a cylindrical recess 18 which constitutes a hydraulic cylinder in which operates the cylindrical plunger 12.

The plunger 12 has a press plate 20 which 65 limits its downward movement and to which is secured a press head 21 which constitutes the movable head of a press. It has a pair of upwardly extending press blocks 22 which are adapted to coöperate with the mold as 70 hereinafter explained.

The stationary press head 13 is securely held in position by studs or heavy tie bolts 23 shown in Fig. 2. A pair of mold supports 24 are adjustably connected to the stationary press head 13 from which they are depended. In the lower ends they are provided with slots 25 constituting guideways to coöperate with the mold. The wedge bar 26 or other suitable means is employed for 80 elevating the supports to clamp the mold against the stationary press head before the movable press head is actuated.

My present invention is not concerned 85 with the structure of the press apart from the mold and while I have shown a simple press having only one pair of coöoperating heads the molds of my invention are adapted to be used in a multiple arrangement in connection with presses such as that shown 90 and described in my copending application to which reference has already been made, where the stationary movable press heads are at a considerable distance apart and the plurality of floating press heads are interposed so that a large number of molds may 95 be received at one time.

Referring now to Figs. 3, 4 and 5, in addition to Figs. 1 and 2, the mold 14 comprises a frame 30 having side flanges 31 100 in which coöperate with the slots 35 in the mold support, an intermediate partition 32 which divides the mold into two parts, and inwardly extending flanges 33 at the bottom of the frame.

The partition 32 is enlarged at the bottom to form flanges or ledges 34 which correspond to the flanges 33 and coöperate therewith in holding a pair of removable mold blocks 35. These blocks may be 110

formed to constitute the mold surfaces, or mold plates 36 may be mounted thereon as shown in Figs. 3 and 4. These plates are alike and each of them is tapered in thickness from one end to the other and has upwardly extending projections 37 which constitute cores to reduce the weight of the material in the thicker portion of the shingle.

10 The formation of the mold plate will be apparent from the formation of the shingle as shown in Fig. 7.

15 The side walls of the mold are notched at 38-39 and the partition 32 is correspondingly notched at 40-41. This is for the purpose of spacing the exposed portion of the shingle as it is laid on the roof.

20 The plates 36 are reversed in position and the notches 38 and 40 are offset from the center of the shingle, their position corresponding to the desired position of the notches in the shingle. These are preferably located at the line of overlap. In other words that portion of the shingle which is 25 covered is laid edge to edge while the exposed portions are spaced apart.

25 By forming the mold as above indicated, I am able to produce a pair of identical shingles in each mold while at the same time 30 the pressure on the press heads is such as to avoid any tendency to distort or strain the press.

35 Furthermore, by disposing the core projections as indicated, I am able to maintain a substantial uniform distribution of weight over the entire shingle and consequently the material used in molding this shingle is subjected to uniform pressure with the 40 result that a uniform and commercially valuable product is obtained.

Variations in size and arrangement of parts and other modifications may be effected within the spirit and scope of my in-

vention, and I intend only such limitations as are indicated in the appended claims.

45

What I claim is:

1. A press mold comprising a mold frame having a bottom flange, and a transverse partition in the center having lateral projections constituting corresponding flanges, a mold block removably mounted in each portion of the frame, and a pair of identical mold plates mounted in reverse position on the respective mold blocks.

50 2. A press mold comprising a mold frame having a bottom flange and a transverse partition in the center having lateral projections constituting corresponding flanges, a mold block removably mounted in each portion of the frame, and a pair of tapered mold plates reversely mounted on the respective mold blocks to produce a pair of tapered objects without producing an out of line reaction when the press is operated.

55 3. A press mold for tapered shingles comprising a mold frame having a bottom flange, and a transverse partition in the center having lateral projections constituting corresponding flanges, a mold block removably mounted in each portion of the frame, and a pair of press plates each tapered from end to end and having upwardly extending lugs or core projections to reduce the weight of the thicker portion of the shingle.

60 4. A press mold comprising a mold frame having a transverse partition in the center, a mold block removably mounted in each portion of the frame, and a pair of tapered mold plates reversely mounted on the respective mold blocks to produce a pair of tapered objects without producing an out of line reaction when the press is operated.

65 In witness whereof, I have hereunto set my hand this 27th day of August, 1917.

CURT R. BURKHARDT.
